(22) Filed: **Aug. 21, 2000**

The ornamental design for a ball-point pen, as shown and described.

(30) **Foreign Application Priority Data**

DESCRIPTION

Feb. 23, 2000 (IT) FI00O0012

FIG. 1 is a front elevational view of a ball-point pen showing my new design with the writing tip retracted;

(51) **LOC (7) Cl.** **19-06**

FIG. 2 is a side elevational view of FIG. 1, the opposite side being a mirror image thereof;

(52) **U.S. Cl.** **D19/51; D19/48; D19/56;**

FIG. 3 is a rear elevational view of FIG. 1;

(58) **Field of Search** D19/35, 36, 41-51,

FIG. 4 is a front elevational view of my design of FIG. 1 with the writing tip exposed;

D19/53-58, 81-85; 401/98, 99, 100-103,

FIG. 5 is a fragmentary view of the top of the cap;

106-117, 209, 202, 262, 243-247; 24/10 R,

FIG. 6 is a front perspective view of the cap member shown separately for ease of illustration;

11 R, 11 PP, 11 CC, 11 CT, 11 C, 11 F,

FIG. 7 is a front and side perspective view of FIG. 6;

11 M, 11 P

FIG. 8 is a side perspective view of FIG. 6;

(56) **References Cited**

FIG. 9 is a side and rear perspective view of FIG. 6; and,

U.S. PATENT DOCUMENTS

FIG. 10 is a rear perspective view of FIG. 6.
